UNITED STATES PATENT OFFICE.

LORNE A. GRIFFIN, OF EVANSTON, ILLINOIS, ASSIGNEE TO AMERICAN STEAM CONVEYOR CORPORATION, OF CHICAGO, ILLINOIS, A CORPORATION OF NEW YORK.

ELBOW FOR ASH-CONVEYER SYSTEMS.

1,331,988.

Specification of Letters Patent. Patented Feb. 24, 1920.

Application filed October 20, 1919. Serial No. 332,042.

To all whom it may concern:

Be it known that I, LORNE A. GRIFFIN, a citizen of the United States, and resident of Evanston, in the county of Cook and State 5 of Illinois, have invented a certain new and useful Improvement in Elbows for Ash-Conveyer Systems, of which the following is a full, clear, and concise description, reference being had to the accompanying drawings, forming a part of this specification.

My invention relates to ash conveyers of the conduit type wherein the ash is conveyed through the conduit by the action of a fluid, such as steam, compressed air or water, and 15 has for its general object the provision of improved means for facilitating the renewal of those portions of the conduit which, during the operation of the conveyer system are subjected to the abrasive action of the ashes.

20 In the installation of conveyer systems of this class, it is necessary, in most cases, to provide both horizontal and vertical pipe lines with the result that elbows, or at any rate, more or less abrupt bends or turns must be employed between the pipe lines extending 25 in different directions. The presence of these elbows or abrupt turns is, of course, accompanied by a very great degree of wear, due to the abrasive action of the ashes at the 30 point where the direction of flow thereof is abruptly changed. Because of the excessive wear on the elbow, it has been the practice to provide elbows comprising removable wear liners or backs which are subject to many 35 objections among which are, high cost of manufacture and upkeep.

It is the general object of the present invention to provide a sectional elbow of the class described, in which those sections subjected 40 to the greatest wear may be easily and quickly removed and renewed.

These, and other objects of the present invention will be pointed out in detail in connection with the accompanying drawings,

45 wherein—

Figure 1 is a side elevational view showing portions of horizontal and vertical pipe lines and the sectional elbow of my invention affording communication between the 50 pipe lines;

Fig. 2 is an enlarged cross-sectional view of the improved elbow shown in Fig. 1;

Fig. 3 is a view similar to Fig. 1 showing

the semi-cylindrical throat section of the elbow removed from the conveyer system, 55 and.

Fig. 4 is a view similar to Fig. 2 showing a modified arrangement of the elbow.

Similar characters of reference refer to similar parts throughout the several views. 60

Referring, first, to Fig. 1,—5 designates a horizontal run of pipe and 6 a vertical run. 7 designates the improved elbow of my invention which is preferably made up of the five semi-cylindrical sections shown at a, b, 65 c, d and e. The horizontal conduit 5 extends to some point in a boiler room, where it is provided with hoppers for the reception of the ashes which are to be conveyed. The vertical run of conduit 6 extends upwardly 70 to a point where the ashes are to be deposited, as for example, an ash tank.

The direction of flow of the ashes through the conduit system is shown by arrow, 8, and in the preferred form of the invention, this 75 flow is caused by the injection of steam in the direction indicated. The steam nozzle employed for injecting the steam may be located at any desirable point in the conveyer system, and I have not considered it necessary, therefore, to show the steam nozzle. If desired, the steam nozzle may project upwardly into the elbow 7 between the sections c and e.

In the preferred form of the invention, the 85 conduits 5 and 6 are made up of several semi-cylindrical sections as shown, each of which is provided with the end flanges 9—9 and slide flanges 10—10, adapted for coöperation with similar flanges of adjacent sections 90 for the purpose of providing tight joints between the several sections. The several sections may be securely locked together by a plurality of bolts, as shown, or may be secured to a support as disclosed and 95 claimed in my co-pending application Serial No. 310,072, filed July 11th, 1919.

Referring now to Fig. 2 which shows the detailed construction of the improved elbow of my invention, the outlet end or conduit 100 of the elbow is formed by two coöperating semi-cylindrical sections a and b, each of which is provided with the end flanges shown at 9—9, adapted for coöperation with similar flanges of adjacent sections. The 105 semi-cylindrical throat section a coöperates

with the angular semi-cylindrical section *d* to provide the inner half of the elbow. The outer half of the elbow is formed by semi-cylindrical sections *b* and *c* and the end section *e*, which as is most clearly shown in this figure, is disposed at right angles to the intake opening of the elbow. Due to the excessive abrasive action of the ashes on the end section *e*, it is desirable that this section 5 be reinforced or slightly thicker than the remaining sections, as clearly shown in the drawings. I have found that the inner throat section *a* of the outlet end of the elbow is subjected to excessive abrasive action 10 of the ashes, due probably to the fact that when the ashes strike against the end section *e*, they are caused to rebound diagonally across the elbow and strike against that portion of the conduit formed by section *a*. 15 For this reason, the section *a* is made considerably thicker than the remaining sections, as illustrated. To permit easy and quick removal of the section *a*, which, due to the abrasive action above referred to requires renewal frequently, I provide the inclined end face shown at 11, adapted for 20 cooperation with a similar face provided on the upper end of the section *d*. This arrangement prevents any binding between the sections when the section *a* is to be removed. To seal the several joints formed between the conduit sections, the joints are filled with grout made up of a fibrous and cementitious fireproof composition, which may be of the 25 kind and class described in patent to James A. Daviess, No. 1,278,869. If desired, the end flanges 9-9 of the sections may be grooved or serrated, as shown, for the purpose of holding the grout in place between 30 the sections.

In the modified arrangement shown in Fig. 4, the elbow is made of one piece, except for the inner wall of the throat of the elbow forming the outlet conduit, which is 45 formed by a semi-cylindrical section *a'*, similar in all respects to the corresponding section *a* shown in Fig. 2. In this modification, I have shown the horizontal and vertical runs of pipe 5' and 6' made up of whole 50 sections as distinguished from the semi-cylindrical sections shown in Fig. 1.

From the above it will be observed that any section of the elbow may be removed and renewed very easily and quickly and that 55 the removal of any section forming part of the elbow does not affect proper support of the vertical pipe. Fig. 3 shows the section *a* removed and the weight of the vertical pipe 6 sustained by the sections *b* and *c*. If 60 the section *b* or *c* is removed, the weight of

the vertical pipe is carried by the sections *a*, *d* and *e*.

Having thus described my invention, what I claim as new and desire to secure by Letters Patent of the United States is:—

1. An elbow for ash conveyer systems comprising a pair of semi-cylindrical sections forming an intake conduit for the elbow, a pair of semi-cylindrical sections forming an outlet conduit for the elbow, a semi-cylindrical section forming the outer wall of the elbow, and detachable means for locking the several sections, whereby any one of said sections may be removed and replaced. 65

2. An elbow for ash conveyer systems comprising a pair of semi-cylindrical sections coöperating to form an outlet conduit, an angular semi-cylindrical section co-extensive with one of said first mentioned sections, a semi-cylindrical section coöperating with the angular section to provide an inlet conduit, an end section extending at right angles to the inlet conduit and detachable means for locking the several sections in position, whereby any of said sections may be removed. 75

3. A sectional elbow for ash conveyer systems comprising an angular semi-cylindrical section forming the inner half of the elbow, a plurality of semi-cylindrical sections forming the outer half of the elbow, and means for holding the several sections in position. 80

4. A sectional elbow for ash conveyer systems comprising an angular semi-cylindrical section forming the inner half of the elbow, a semi-cylindrical section coöperating with the angular section to provide an inlet conduit, an end section extending at right angles to the inlet conduit, and means for locking the several sections in position. 85

5. An elbow for ash conveyer systems including a removable semi-cylindrical section forming the inner half of the elbow outlet and having end flanges adapted for coöperation with flanges of adjacent sections to provide tight joints between the sections. 90

6. An elbow for ash conveyer systems including a removable semi-cylindrical section forming the inner half of the elbow outlet, said section having end flanges adapted for coöperation with flanges of adjacent sections to provide tight joints between the sections and having an oblique end face facilitating removal of said section. 105

In witness whereof, I hereunto subscribe my name this 18th day of September, 1919.

LORNE A. GRIFFIN.
